CLAIM

The ornamental design for an automotive wheel, as shown and described.

DESCRIPTION

FIG. 1 is a left, rear-isometric view of the wheel showing a first spoke assembly;

FIG. 2 is a right, rear-isometric view of the wheel showing a second spoke assembly; and

FIG. 3 is an exploded view of the wheel; and,

FIG. 4 is a cross-sectional view of the wheel.
The broken lines depict unclaimed portions of the automotive wheel and form no part of the claim.

1 Claim, 4 Drawing Sheets

FIG. 1
